EDWIN W. GOESER, OF LOS ANGELES, CALIFORNIA, ASSIGNOR TO EMSCO DERRICK & EQUIPMENT COMPANY, OF LOS ANGELES, CALIFORNIA, A CORPORATION OF CALIFORNIA

ANTIFRICTION DEVICE FOR DRILL PIPE

Application filed May 14, 1928. Serial No. 277,630.

This invention has to do with the oil well drilling industry and consists of a new and improved anti-friction device for drill pipe.

In order to explain the advantages of the invention the well drilling industry will be briefly referred to. The well is drilled by means of a bit secured to the lower end of a drill pipe, which drill pipe extends through the floor of the derrick and is rotated by means of a rotary machine thereon. The drill pipe consists of stands of pipe about 80 feet long, these stands of pipe being connected together by tool joints. The tool joints are somewhat larger in diameter than the lengths which make up the drill pipe.

After the well has been drilled to a certain depth, it is common practice to install a well casing, the lower end thereof being cemented in place to exclude water. The next section of the hole is then drilled by means of a bit which is lowered through the well casing. When the drill pipe is rotated the tool joints will engage the walls of the well casing, and this results in wear on the tool joints and also on the well casing. In many instances the well casing has been perforated so that water leaks into the well so that an emulsion is produced.

Furthermore, the friction between the well casing and the tool joints consumes considerable power and in some instances has been great enough to offer sufficient resistance to the rotation of the drill pipe to cause twist-offs especially so if the well bore deviates from the vertical.

It is the general object of this invention to provide an anti-friction device for reducing the friction and wear between the drill pipe and the well casing.

When an anti-friction device is in operation in a well, and the drill pipe is being rotated, the part thereof which engages the well casing is subjected to friction on a horizontal plane; and if the contact with the casing is very narrow (such as when balls are used as bearing means) or if the well bore deviates from the vertical, there is a local outward pressure against the well casing which tends to form an annular depression therein. This action against the well casing weakens it con-

siderably. For the reason just explained there is less wear on the casing when a sleeve type of bearing is used. A sleeve type of bearing has a large area of contact which obviates the forming of depressions in the well cas- 35

When the drill pipe is being raised or lowered in a well, the friction on the anti-friction device is in a vertical plane. In the sleeve type of anti-friction device friction on a horizontal plane only is absorbed and there is no provision for absorbing the friction on a vertical plane. For this reason the sleeve of the sleeve type of bearing will not rotate during the raising or lowering and this results in the 40 45 wearing of a flat strip on the sleeve, which causes the sleeve to have an irregular shape.

With a view of overcoming the disadvantages enumerated above, I provide an anti-friction device which will not form depressions during rotation of the drill pipe and which will not be worn irregular in shape during lowering or raising of the drill pipe.

The object of my invention is accomplished by providing the anti-friction device with a 45 bearing means for absorbing the friction during a rotation of the drill pipe and with a bearing means for absorbing the friction during the lowering or raising of the drill pipe.

It is another object of this invention to 50 provide an anti-friction device which combines a sleeve bearing and a ball bearing.

It is a still further object of the invention to provide an anti-friction device in which the parts are secured together on the 55 neck of a supporting part by a clamping part which is screwed onto the supporting part.

It is an additional object of the invention to provide an anti-friction device in which the parts are designed so that they may all 60 be assembled from one end of the supporting part.

In the description of the invention which follows various other objects of the invention will be made known.

Referring to the accompanying drawings in which a preferred embodiment of this invention is illustrated,

Fig. 1 is a diagrammatic view illustrating 65 100 the invention.

Fig. 2 is an enlarged view partly in section, showing the details of the invention.

Fig. 3 is a section taken on the line 3—3 of Fig. 2.

5 Fig. 4 is a section taken on the line 4—4 of Fig. 2.

Referring particularly to Fig. 1, the numeral 11 represents a drill pipe which is extended through a well casing 12. The upper 10 and lower ends of the drill pipe 11 are not shown but according to standard rotary drilling practice the lower end of the drill pipe is provided with a bit and the upper end thereof is driven by a rotary table of an oil 15 well derrick. The different sections of the drill pipe 11 are connected together by tool joints or coupling members 14 which embody the features of this invention.

Referring particularly to Figs. 2 to 4 inclusive, the details of the invention will be described.

The tool joints 14 consist of parts 15 and 16 which are threadedly connected at 17 to lengths of pipe 18 which comprise the drill 20 pipe 11. The parts 15 and 16 are connected together by a body or supporting part 19. One end of the supporting part 19 is internally threaded to receive a threaded portion of the part 15, and the other end of the body 25 19 is provided with an externally threaded portion 20 which is screwed into an internally threaded portion of the part 16. The body 19 at the upper end is provided with a cylindrical neck 23. At the lower end of the neck 23 30 is an annular shoulder 24 and at the upper end thereof is the externally threaded portion 20. The body 19 is also provided with a central opening 26 to permit a flushing fluid to pass outward through the pipe 11.

40 Carried on the neck 23 of the body 19 is the bearing assembly which embodies certain important features of the invention. Arranged on the neck 23, adjacent to the shoulder 24 is a ball bearing construction 30 and arranged on the neck 23 adjacent to the part 16 and the threaded end 20 is a ball bearing construction 31. Each of the ball bearing constructions includes a race formed of two complementary race-parts 32 which cooperate to provide an annular channel 33 in which balls 34 of the ball bearing constructions are retained. The channels 33 surround the balls to the extent that they cannot be removed from place when the race-parts 32 are assembled as shown in the drawings.

Arranged on the neck 23 between the ball bearing constructions 30 and 31 is a sleeve bearing construction 36. The sleeve bearing construction 36 has an inner non-rotatable 50 sleeve 37 which surrounds the neck 23 in contact therewith. Surrounding the inner sleeve 37 is an outer rotatable bearing sleeve 38 which is journaled on the inner sleeve 37 by bearing rollers 39. The bearing rollers 39 are 55 arranged in upper and lower pairs, and are

spaced apart from each other by roller spacing rings 40. The roller spacing rings 40 are cylindrical and are provided with elongated slots 41 in which the bearing rollers 39 are situated.

The race members 32 and the inner non-rotatable sleeve 37 are pressed onto the neck 23 of the body 19. When the parts are assembled, as shown in Fig. 2, the end of the part 16 engages the adjacent race member 32 and clamps the parts 32 and 37 against the shoulder 24 of the body 19. The part 16 constitutes the clamping part of the invention.

The race members 32 adjacent to the sleeve bearing construction 36 form a channel in which the moving parts of the sleeve bearing construction 36 are retained. Upon the inspection of Fig. 2 it will be seen that the inner sleeve 37 is slightly longer than the outer bearing sleeve 38 so that the sleeve 38 has clearance to rotate.

The ball bearing constructions 30 and 31 constitute the bearing means of the invention for absorbing longitudinal friction and they also constitute the means of the invention for protecting the bearing sleeve 38 from wear. The bearing balls 34 of the ball bearing constructions 30 and 31 are adapted to have a circumferential line contact with the wall of the well casing 12. In designing the invention the diameter of this circumferential line contact is made the same as the diameter of the engaging face of the sleeve bearing 38. The sleeve bearing 38 constitutes the bearing means of the invention for absorbing rotational friction or horizontal friction.

As shown in Fig. 1, the anti-friction bearing assembly of the invention is shown in contact with the left side of the well casing 12. In the ordinary anti-friction device which employs only ball bearing construction, the contact between the bearing and the wall of the well casing is a line contact and a depression is quickly formed in the well casing, which considerably reduces its strength. In the present invention the sleeve 38 provides a large area of contact between the bearing and the pipe so that it is impossible for the ball bearings 30 or 31 to cause depressions in the well casing 12.

When the drill pipe 11 is being lowered or raised in the well there is a longitudinal friction. As pointed out heretofore, in the ordinary sleeve type anti-friction bearing the part of the sleeve which engages the well casing is worn flat so that the sleeve is irregular in shape. In my invention the ball bearing constructions 30 and 31 prevent excessive frictional wear on the sleeve 38. This is because of the fact that during a longitudinal movement of the drill pipe the bearing balls 34 are free to rotate. The anti-friction device is guided over the contour of the well casing 12 by means of the ball bearing constructions 30 and 31.

It is possible to construct the device of the invention on the ball bearing constructions either at the top or at the bottom of the sleeve bearing construction 36. The preferred form of construction, however, has the ball bearing constructions 30 and 31 at the opposite ends of the ball bearing construction 36. The invention operates most satisfactorily when the circumferential line contact of the ball bearing constructions 30 and 31 has the same diameter as the bearing surface of the bearing sleeve 38. It is possible to change these diameters slightly, and good results are obtained if the diameter of the circumferential line contact of the ball bearing constructions 30 and 31 is slightly larger than the sleeve bearing construction 36. When such a construction is utilized the bearing balls 34 will make slight depressions in the well casing, but these depressions are not great enough to cause appreciable injury to the well casing. During the raising and lowering of the drill pipe the bearing balls 34 will keep the sleeve 38 out of contact with the well casing so that there is no frictional wear on the sleeve 38.

The feature of combination of the bearing means for absorbing rotational friction and the bearing means for absorbing longitudinal friction does not require the assembling features also present in the invention. As an example, these features are independent of the manner in which the parts are clamped in place. It is therefore obvious that this feature of the invention may embody any other designs of anti-friction devices which do not also possess the features of assembly of this invention.

Features of design which relate to the manner of assembling the parts of the invention and the manner in which they are secured on the supporting part 19 are independent of the features of the types of bearings used in the invention. Therefore it will be obvious that these features of design and assembly may be utilized in constructions independently of the combination of the bearing for absorbing rotational friction and the bearing for absorbing longitudinal friction.

I claim as my invention:

1. An anti-friction device for drill pipe comprising: a sleeve bearing for absorbing friction during a rotary movement of the drill pipe; and a bearing above and a bearing below said sleeve bearing for absorbing friction during a longitudinal movement of the drill pipe.

2. An anti-friction device for drill pipe comprising: a sleeve bearing adapted to absorb friction during a rotary movement of the drill pipe; and means on opposite sides of said sleeve bearing and independent thereof for protecting said sleeve bearing from wear during a longitudinal movement of the drill pipe.

3. An anti-friction device for drill pipe

comprising: a sleeve bearing having an external contact face; and a ball bearing mounted adjacent to said sleeve bearing, said ball bearing having the same external diameter of circular line of contact as said external contact face of said sleeve bearing. 70

4. An anti-friction device for drill pipe comprising: supporting means; a pair of spaced bearings on said supporting means, said spaced bearings being in position for external engagement during movement of the drill pipe in longitudinal direction; and a sleeve bearing retained adjacent to and between said spaced bearing means and on said supporting means, said sleeve bearing being adapted to engage the well casing during rotation of said drill pipe. 75 80

5. An anti-friction device for drill pipe comprising: a supporting part having a neck, a shoulder at one end of said neck and threads at the other end of said neck; a bearing assembly placed on said neck, having a movable sleeve adapted to engage a well casing and ball bearings adapted to engage said well casing; and a clamping part screwed onto said supporting part, said clamping part clamping the non-movable parts against said shoulder. 85 90

6. An anti-friction device for drill pipe comprising: a supporting part having a neck, a shoulder at one end of said neck and threads at the other end of said neck; a bearing assembly arranged on said neck; ball bearings mounted on said neck above and below said bearing assembly, said ball bearings being adapted to engage a well casing; and a clamping part screwed on the end of said neck, said clamping part clamping said ball bearing against said bearing assembly and said bearing assembly against said shoulder. 95 100 105

7. An anti-friction device for drill pipe comprising: a supporting part having a neck, a shoulder at one end of said neck and threads at the other end of said neck; a ball bearing seated on the shoulder of said neck; a sleeve bearing assembly arranged on said neck above said ball bearing, said sleeve bearing having movable and non-movable parts; a ball bearing disposed above said sleeve bearing; and a clamping part screwed onto said supporting part for clamping said bearings together on said neck. 110

8. An anti-friction device for drill pipe comprising: a supporting part having a neck, a shoulder at one end and threads at the opposite end of said neck; a bearing assembly on said neck seating on said shoulder and having movable and non-movable parts; a ball bearing arranged on said neck above said bearing assembly; and a clamping part screwed onto said supporting part, said clamping part clamping said ball bearing against said bearing assembly and the non-movable parts of said bearing assembly against said shoulder. 115 120 125 130

9. An anti-friction device for rotary drill pipe comprising: a supporting part and a pipe joint part associated therewith, a neck on said supporting part having threads at one end and a shoulder at the other end; a ball bearing assembly seated on said shoulder; and a sleeve bearing assembly disposed on said neck above said ball bearing assembly, said pipe joint part adapted to be screwed onto the threaded end of said neck and against said sleeve bearing assembly for clamping said bearing assemblies on said supporting part.
10. An anti-friction device for rotary drill pipe comprising: a supporting part and a pipe joint part associated therewith, a neck on said supporting part having threads at one end and a shoulder at the other end; a ball bearing seated on the shoulder of said neck; a sleeve bearing mounted on said neck and engaging said ball bearing; and a ball bearing mounted adjacent said sleeve bearing, and said pipe joint part adapted to be screwed onto said supporting part for clamping said bearings upon said neck.

In testimony whereof, I have hereunto set my hand at Los Angeles, California, this 1st day of May, 1928.

EDWIN W. GOESER.
